SPINDLING DEVICE

Everett M. Barnes and Clarence E. Barnes,
New Paris, Ohio

Application February 24, 1947, Serial No. 730,624

4 Claims. (Cl. 93—93)

1

The invention herein shown and described is adapted to be used in connection with a banding mechanism which is shown and described in our application entitled Banding mechanisms, Serial No. 699,122, filed September 25, 1946, the principal object of the invention being to provide means receiving the folded and banded paper strips from the banding mechanism as the same are expelled therefrom.

Another object of the invention is the provision of means positioned in adjacent relation with a banding mechanism for orderly spindling paper strips thereon and thereby saving the time ordinarily required to remove the same from a receptacle, and to arrange them in orderly fashion.

A further object is the provision of a receiving pin which is removable from the device and which has one end thereof provided for the transfer of the paper strips therefrom onto a second pin.

A still further object of the invention is the provision of a device which is simple of construction, and which is economical to manufacture.

Other objects and particular advantages of the invention will become further apparent in the course of the following description, and that which is new will be pointed out in the appended claims.

The preferred, and most satisfactory manner of carrying out the principles of the invention in a practical manner is shown in the accompanying two sheets of drawings, in which:

Figure 1 is a side elevation of the device, with the same being shown in connection with a banding mechanism and being secured to the base member of the banding mechanism.

Figure 2 is a detail front elevation of the device, as taken from line 2—2 of Figure 1.

Figure 3 is a top plan view, as taken from line 3—3 of Figure 1.

Figure 4 is a detail of one of the paper strips to be spindled onto the device as the strip is expelled from the banding mechanism.

Figure 5 is a detail side elevation of the upper portion of the device similar to that shown in Figure 1 but on an enlarged scale, and showing one of the paper strips engaging the spindling device.

Figure 6 is a front elevation of the upper portion of the device, and with the same being taken from line 6—6 of Figure 5.

Figure 7 is a top plan view of the upper por-

2

tion of the device, taken from line 7—7 of Figure 5.

Figure 8 is a detail sectional-elevational detail of the device, taken on line 8—8 of Figure 6.

5 Figure 9 is an elevational detail showing the receiving pin positioned on a second pin for the purpose of transferring the threaded paper strips from the receiving pin onto the second pin.

Like characters of reference designate like parts throughout the several views.

10 In order that the advantages of the invention may be more fully understood and appreciated, we will now take up a detailed description thereof, in which the same will be more fully set forth.

15 The spindling device has a main body member comprised of a bar 8 having forwardly-extending offset portion 9 formed therein, and with a lower portion 10 being formed below the offset 9. A forwardly-extending foot portion 11 is formed at 20 the lower end of the body member and has an aperture formed therein for the reception of the lower end of receiving pin 20.

The upper end portion of the body is angularly disposed forwardly and forms an incline 12, the 25 purpose of which will be more fully set forth hereinafter.

A guide member 13 is secured to one side of the upper portion of the body and is secured thereto by means of screw 14. The upper portion 30 15 of guide member 13 is curved toward the banding mechanism, with a curved forward extension 16 being formed thereon. The curved forward portion has a downwardly and rearwardly extended portion 17 formed thereon.

35 It will be noted, by referring especially to Figures 5 and 8, that the upper end portion of incline 12 is positioned slightly above the tangential line of gripping rollers 4 and 5, and also that the lower surface of the portion 17 is slightly below the tangential line of the rollers, and with the extreme rear end of portion 17 being slightly above the tangential line of the rollers.

The body member is secured in fixed relation to the banding mechanism by means of screw 18 45 being threaded into the base member 6. Pivotal movement of the body member on screw 18 is prevented by means of pins 19 which extend through the body member and into the base 6, as more clearly shown in Figures 1 and 2.

50 A receiving pin member 20 is removably set into the aperture formed in the foot portion 11, and with a conical-shaped aperture 21 being formed in the lower end of the pin 20, as more clearly shown in Figures 1, 2, and 9. The upper end portion of pin 20 is pointed, with the point

being located at substantially the same level as the tangential line of rollers 4 and 5. It will be further noted, by referring to Figures 2, 3, 6, and 7, that the pointed end of pin 20 is located substantially midway between portion 12 and the outer ends of rollers 4 and 5.

In the operation of the device, folded paper strips 24 (having apertures 25 formed therethrough near one end thereof) are progressed through the banding mechanism wherein the folded portions are banded and are passed from a pair of rollers (not shown) into engagement with rollers 2 and 3 and therebetween, after which the strips are engaged by rollers 4 and 5. As the paper strips progress, the outer ends thereof project outwardly beyond the ends of the rollers. As the paper strips 24 are engaged between rollers 4 and 5, the outer ends of the strips engage the incline 12 of the bar 8, and with the continued forward movement of the strips, the outer ends thereof are bent slightly upward in their passage over the incline surface 12. The forward edges of the paper strips, after passing between rollers 4 and 5, engage the under surface of portion 17 of the guide member and with the engagement therewith forcing the leading edges of the strips slightly downward. The action of the incline 12 and the under surface of portion 17 causes the apertures 25 of the strips 24 to engage the point of the receiving pin 20 and, upon engagement with the point, the strips slide downwardly on the receiving pin.

When a sufficient number of paper strips have accumulated on the receiving pin, the pin is removed from the foot 11, after which the paper strips are transferred to a second pin 22 which has a base 23 secured to the lower end thereof. Pin 22 has a point formed at the upper end thereof and which is adapted to engage the conical-shaped aperture 21 of receiving pin 20, as more clearly shown in Figure 9. After the paper strips have been transferred to pin 22, pin 20 is again reset into the aperture formed in foot 11.

It will be obvious that considerable time is saved by the use of the spindling device over the conventional manner of permitting the paper strips to fall into a receptacle from the banding mechanism, after which they must be removed and stacked or otherwise rearranged. With the present invention, the strips are merely transferred from the receiving pin to a second pin for storage, or for other purposes.

Although the preferred embodiment of the invention has been shown and described, we desire that it be understood that minor changes may be made in the several parts and in the arrangement thereof, insofar as the changes therein may fall within the scope of the appended claims.

Having now shown and described the invention, what we claim, is:

1. In a spindling device, the combination of a body member, an incline portion formed at the upper end of the body member, a guide secured to the upper portion of the body member, a

foot portion formed on the lower end of the body and having an aperture formed therein, a receiving pin having its lower end inserted into the aperture of the foot portion, with the upper end portion of the receiving pin forming a point, and with the point being located substantially midway between the incline portion of the body and the guide member.

2. In combination with a banding machine having rollers extending outwardly therefrom, with paper strips passing between the rollers and with one end of the paper strips being perforated and extending outwardly beyond the ends of the rollers, a spindling device comprising a body member, a foot portion formed on the body member, a receiving pin having its lower end set into the foot member and with the upper end of the receiving pin terminating in a point with the point being located adjacent the outer end portions of the rollers and in alignment with the path of the perforations formed in the paper strips, and with guide means formed on the body member guiding the perforations of the paper strips onto the upper end of the receiving pin.

3. In combination with a banding mechanism having rollers extending outwardly therefrom, with paper strips having perforations formed near one end thereof passing between the rollers with the perforated ends of the paper strips extending outwardly and beyond the outer ends of the rollers, a spindling device located adjacent the outer ends of the rollers, an incline surface formed on the upper end of the body portion of the spindling device, with the incline surface being adapted to raise the outer ends of the paper strips in their passage thereover, a guiding means secured to the body member and being engageable by the paper strips, with the guiding means forcing the leading edges of the paper strips downwardly upon engagement therewith, a receiving pin having its upper end in alignment with the travel of the perforations of the paper strips, and with the incline surface and the guiding means providing means engaging the perforations of the paper strips on the upper end of the receiving pin.

4. In combination with a banding mechanism having rollers therein, and with paper strips having apertures formed in one end thereof and progressed between pairs of rollers, a spindling device located adjacent the rollers, with said spindling device being composed of a bar member, an incline formed at the upper end of the bar member, guide means secured to the upper portion of the bar member and extending therefrom toward the rollers of the banding mechanism, a receiving pin positioned in a foot portion of the bar member and having a paper strip-engaging point formed at the upper end thereof, with the point being positioned between the incline portion and the guide means, and with the point of the receiving pin being engageable by the apertures formed through the paper strips.

EVERETT M. BARNEs.
